GASEOUS ELECTRIC DISCHARGE DEVICE

Nicolaas W. H. Addink, Eindhoven, Netherlands,
assignor to General Electric Company, a corporation of New York

Application August 23, 1937, Serial No. 160,549
In Germany September 3, 1936

1 Claim. (Cl. 176—122)

The present invention relates to gaseous electric discharge devices generally and more particularly the invention relates to such devices having a luminescent material associated therewith to supplement and complement the light emitted by the discharge in the device.

A large variety of luminescent materials, that is, fluorescent or phosphorescent materials, are useful in transforming the rays of shorter wave length, such as ultra violet rays, emitted by the discharge into rays of longer wave length within the visible range. Such materials include tungstates, such as calcium tungstate; sulphides, such as zinc sulphide or calcium sulphide, and oxides, such as zinc oxide. These materials are mounted in light receiving relation to the lamp device as by being applied to the container of the lamp device, a bulb enclosing the lamp device or on a reflector for the lamp device, the location thereof being determined by the characteristics of the particular type of material used and by other factors. I have observed that the light output of the luminescent sulphides diminishes and the color of the light emitted thereby changes after a comparatively short period of irradiation. This is particularly noticeable when the density of the light incident at the surface of the luminescent sulphide is high as is the case when such materials are irradiated by the light from a high pressure mercury vapor discharge lamp.

The object of the present invention is to provide a lamp unit comprising a luminescent sulphide and a gaseous electric discharge lamp device in which the sulphide retains its original spectral emission and a high light output substantially unchanged for a long useful life. Still further objects and advantages attaching to the device and to its use and operation will be apparent to those skilled in the art from the following particular description.

I have discovered that the loss in the light output and the change in the color of the light emitted by luminescent sulphides during irradiation by the light from a gaseous electric discharge device is caused by the presence of halides, such as sodium chloride and potassium chloride, in the luminescent sulphide. These deleterious materials are present in the commercially obtainable luminescent sulphides in extensive use in the art. Having discovered the cause of the difficulty the solution of the problem is comparatively simple. Since these deleterious materials are soluble in water they can be removed by washing the luminescent sulphides. When no halide is detectable in the water the luminescent

sulphide is considered to be halide free and, as I have demonstrated, has a long useful life when used in conjunction with gaseous electric discharge lamp devices.

In the drawing accompanying and forming part of this specification an embodiment of the invention is shown in a front elevational, partly sectional view.

Referring to the drawing the lamp unit comprises a gaseous electric discharge lamp device 10 having a tubular container 1 of small bore with thermionic activated electrodes 7 and 8 sealed therein at the ends thereof. Said container 1 consists of a vitreous material having a high softening temperature, such as quartz, and has 15 therein a quantity of mercury, the vapor of which is luminosity producing during the operation of the device, and a starting gas, such as argon. The discharge device is capable of operation with a mercury vapor pressure of 20 atmospheres or 20 higher and is a highly efficient, concentrated light source. Electric discharge devices of this type are described in the co-pending application, Serial Number 46,952 filed October 26, 1935, and reference is had to said copending application 25 for the structural details and operating characteristics of discharge lamps of this type.

The gaseous electric discharge lamp device is mounted in a sealed bulb 2 consisting of one of the usual container glasses, such as a lead or a 30 lime glass. Said bulb 2 has a stem 3 into the press of which the current leads 4 and 5 for the discharge lamp device are fused. Said discharge lamp device is supported in said bulb 2 by said leads 4 and 5. The inner surface of the 35 spherical part of the bulb 2 has a coating 6 thereon consisting of a luminescent sulphide, such as zinc sulphide or cadmium sulphide, which has been washed in distilled water until no halides are detectable in the water. The coating 6 40 is applied to said bulb 2 by methods now known in the art, such as by using a binding agent of phosphoric acid dissolved in methyl alcohol. The bulb 2 is either evacuated or filled with an inert gas, such as nitrogen, after the coating 6 is applied thereto and the discharge lamp device is mounted therein and serves as a heat conservator for the discharge lamp device.

The coating 6 transmits the visible light emitted by the gaseous electric discharge lamp device and transforms certain rays of comparatively short wave length into visible rays of longer wave length to supplement and complement the light emitted by the discharge lamp.

While I have shown and described and have

pointed out in the annexed claim certain novel features of the invention, it will be understood that various omissions, substitutions and changes in the forms and details of the device illustrated and in its use and operation may be made by those skilled in the art without departing from the broad spirit and scope of the invention, for example, other types of discharge lamps which emit rays capable of exciting the luminescent sulphides are used, when desired.

What I claim as new and desire to secure by Letters Patent of the United States, is:—

A lamp unit comprising in combination a gaseous electric discharge lamp device and a luminescent sulphide mounted in light receiving relation to said lamp device, said material being emissive in the visible spectral ranges when irradiated by said lamp and containing halides in such small amounts that the light output and the color of the light emitted by said sulphide is substantially unaffected by said halides for a long useful operating life of the lamp unit.
